UNITED STATES PATENT OFFICE.

JOEL S. WARNER, OF OGDENSBURG, NEW YORK.

IMPROVEMENT IN CARTRIDGE-LOADERS.

Specification forming part of Letters Patent No. 133,607, dated December 3, 1872.

To all whom it may concern:

Be it known that I, J. S. WARNER, of Ogdensburg, in the county of St. Lawrence and State of New York, have invented an Improved Cartridge-Shell Loader for Breech-Loading Fire-Arms, of which the following is a specification:

Figure 1 represents a sectional side view of my improved shell-loader. Fig. 2 is a transverse section on the line *c c*, Fig. 1; and Fig. 3, an end view of the same.

The object of this invention is to produce a portable device but little larger than the cartridge-shell for placing the wads therein; and the invention consists in a tube counterbored to fit over cartridge-shell and provided with a spring-plunger.

In the drawing, *A* represents a plunger, cylindrical, slotted, and inserted within a short tube, *B*. A pin, *a*, fitted transversely through the tube, passes also through the slot of the plunger *A*. *b* is a spring concealed within the upper part of the plunger and bearing against

the pin *a*. A wad, *d*, is placed in tube *B* against the end of plunger, and the latter then forced into the shell *C*, which is fitted into the counterbored end of the tube *B*.

As soon as the plunger is relieved from pressure, spring *b* will withdraw it from shell and place it in position for the next operation.

It will be perceived that this construction allows the cartridge-loader to be readily carried about the person, as well as insures the quick and easy insertion of the wads.

Having thus described my invention, what I claim as new, and desire to secure by Letters Patent, is—

A portable cartridge-shell loader, consisting of tube *B*, counterbored at the lower end and provided with a spring-retracted plunger, as described.

JOEL S. WARNER.
